UNITED STATES PATENT OFFICE.

CHARLES WEINBERG, OF NEW YORK, N. Y.

DESIGN FOR GIMP.

Specification forming part of Design No. **11,330**, dated August 12, 1879; application filed April 24, 1879.
[Term of patent 3½ years.]

To all whom it may concern:

Be it known that I, CHARLES WEINBERG, of the city and State of New York, have invented or produced a Design for Gimp, of which the following is a specification.

Gimp is made with heavy weft-threads and comparatively fine warp-cords or threads; hence, in the appearance of the same the transverse cords are prominent, and the edges of the gimp are composed of semicircles or scallops of greater or less size. This gimp is stiff, and is used principally for furniture.

The object of the present design is to alter the appearance of the gimp, by hiding the heavy transverse cords in places by a chenille surface in sections side by side, lengthwise of the gimp.

In the drawings my said gimp is represented, Figure 1 being a side view and Fig. 2 a section.

The weft-cords *a* and warp-cords or threads *b* are of usual character, and the width of the gimp and the shape of the edges vary.

My design relates to the ornamentation of the gimp, consisting in chenille sections *c*, that are side by side lengthwise of the gimp. The weft-cords, that cross the gimp at intervals, divide the chenille surface into sections, so as to break up the continuity in the appearance

of the velvet-like surface. The chenille surface is composed of one or more chenille warps, that are upon the surface, except where tied down by the weft-cords that pass between one section and the next.

I am aware that tufts have been introduced into gimp at intervals, such tufts being secured by the warp or weft threads. A fabric has also been proposed in which spots of chenille are introduced in different places in the surface. In the first instance the tuft has a different appearance to a chenille section, and in the last instance the flat fabric was not a gimp, and hence had none of the appearances of a gimp.

I claim as my invention—

The design of the gimp herein specified, the same consisting of the heavy weft-threads running crosswise of the material, the thin warp-threads, and the chenille sections running lengthwise of the gimp and separated by the cross weft-threads, and having the ornamental appearance set forth.

Signed by me this 19th day of April, 1879.

CHARLES WEINBERG.
